(57) **CLAIM**

The ornamental design for a snack food mold, as shown and described.

DESCRIPTION

FIG. 1 is a top perspective view of the snack food mold of the present invention;

FIG. 2 is a top plan view of the snack food mold of the present invention; and,

FIG. 3 is a front elevation view of the snack food mold of the present invention, with the right elevation view, left elevation view and rear elevation view being identical to the front elevation view.

The broken line showing a dimple in the center of the mold in FIGS. 1 and 2 is for illustrative purposes only and forms no part of the claimed design. Further, the broken line on the perimeter of FIGS. 1 and 2 and at the bottom of FIG. 3 defines the bounds of the claimed design and forms no part thereof.
